Primary Examiner — Karen E. Eldridge Powers*Assistant Examiner* — Jasmine Mlinarcik**CLAIM**

The ornamental design for a cap for dreadlocks, as shown and described.

DESCRIPTION

FIG. 1 is a rear elevational view of a cap for dreadlocks showing my new design;

FIG. 2 is a front elevation view thereof;

FIG. 3 is a right side elevation view thereof;

FIG. 4 is a left side elevation view thereof; and,

FIG. 5 is a top plan view thereof.

The evenly incremented broken lines represent environmental structure that forms no part of the claimed design. The dash-dot-dash broken lines illustrated within the interior portion of the cap represents the bounds of the claim and does not form part of the claimed design.
